UNITED STATES PATENT OFFICE.

HARRY ZIEGLER, OF ST. LOUIS, MISSOURI, ASSIGNOR TO LEVITT MILLINERY COMPANY, OF ST. LOUIS, MISSOURI, A CORPORATION OF MISSOURI.

DESIGN FOR A HATRACK.

Application filed April 20, 1925. Serial No. 18,177. Term of patent 7 years.

To all whom it may concern:

Be it known that I, HARRY ZIEGLER, a citizen of the United States, residing in the city of St. Louis, State of Missouri, have invented a new, original, and ornamental Design for a Hatrack, of which the following is a specification, reference being had to the accompanying drawing, forming a part thereof, in which the figure is an elevational view of a hatrack embodying my new design.

I claim:

The ornamental design for a hatrack substantially as shown.

HARRY ZIEGLER.
